CLAIM

The ornamental design for a spanner, as shown and described.

DESCRIPTION

FIG. 1 is a perspective view of a spanner showing my design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is the perspective view from another angle thereof;

FIG. 9 is a perspective view (I) of the spanner in a position of use.

FIG. 10 is a perspective view (II) of the spanner in a position of use.

FIG. 11 is a perspective view (III) of the spanner in a position of use.

FIG. 12 is a perspective view (IV) of the spanner in a position of use.

FIG. 13 is a front elevational view of FIG. 12.

FIG. 14 is a perspective view (V) of the spanner in a position of use.

FIG. 15 is the perspective view from another angle of FIG. 14; and,

FIG. 16 is a perspective view (VI) of the spanner in a position of use.
